APPARATUS FOR SUSPENDING AND
RELEASING OBJECTSHerbert C. Roters, Mountain Lakes, N. J., assignor
to Fairchild Camera and Instrument Corpora-
tion, a corporation of Delaware

Application June 10, 1940, Serial No. 339,671

5 Claims. (Cl. 89—1.5)

This invention relates to apparatus for suspending an object in the air and effecting substantially instantaneous release thereof when desired, and more particularly to a device for holding and releasing aerial bombs.

One of the objects of this invention is to provide apparatus for suspending an object and effecting the release thereof which is simple in structure and operation, and which is capable of releasing the suspended object at any desired instant. Another object is to provide apparatus of the above nature which is light in weight, and which may be installed in a relatively limited space, and yet be capable of suspending objects of considerable weight and size. Another object is to provide apparatus of the above nature which may be attached to an aeroplane for instantaneously releasing bombs suspended thereby. Another object is to provide apparatus for holding or suspending a substantial weight in the air for indefinite periods of time, and without danger of prematurely releasing such object. Other objects will be in part apparent and in part pointed out hereinafter.

The invention accordingly consists in the features of construction, combinations of elements, and arrangements of parts as will be exemplified in the structure to be hereinafter described and the scope of the application of which will be indicated in the following claims.

In the drawings, wherein there are shown several embodiments of my invention,

Figure 1 is a side elevation of my bomb supporting and releasing apparatus;

Figure 2 is a side elevation of a modified form of my apparatus;

Figure 3 is a sectional elevation of a magnet which forms a part of my apparatus;

Figure 4 is a horizontal section taken along the line 4—4 of Figure 3;

Figure 5 is a wiring diagram of a control circuit for my apparatus;

Figure 6 is a wiring diagram of a modification of the control circuit for my apparatus;

Figure 7 is a wiring diagram of another modification of a control circuit for my apparatus;

Figure 8 is a sectional elevation of a different type of magnet;

Figure 9 is a side view of the magnet shown in Figure 8;

Figure 10 is a side view of another form of my apparatus;

Figure 11 is an enlarged section taken along the line 11—11 of Figure 10;

Figure 12 is an enlarged section taken along the line 12—12 of Figure 11;

Figure 13 is a wiring diagram for controlling a number of bomb shackles to effect train bombing;

Figure 14 is another wiring diagram for a different type of train bombing control; and,

Figure 15 illustrates an oscillogram showing time of current decay.

Similar reference characters refer to similar parts throughout the various views of the drawings.

Bomb holding and releasing apparatus as heretofore available has been in most instances characterized by complicated and weighty mechanical structure having inherently serious limitations which detract from accuracy in operation. Some of these mechanical systems utilize an electromagnet, energization of which effects releasing operation of the mechanical system. In the use of a device of this character, there is a substantial delay between energization of the magnet and the release of the bomb, and a substantial amount of power is required to operate the magnet. The time delay is undesirable since it is variable, depending on supply voltage, magnet coil temperature, and mechanical friction, all of which are difficult, if not impossible to compensate for. The inability to effect an accurate compensation for these factors results in an error over which the operator has no control. The large amount of power necessary to operate such systems is undesirable as the power source on an aeroplane is usually the storage battery, of limited capacity. This, of course, results in large variations in supply voltage, which naturally augment the variations in time delay. Furthermore, the variations in supply voltage prevent, or make uncertain, the simultaneous release of a number of bombs.

The time delay between energization of the magnet and the release of the bomb in a system such as that just referred to, results because of the interval necessary for the current to reach a strength sufficient to actuate the magnet, and also because of the time required for the magnet plunger to move the necessary distance to effect the mechanical release. This time delay is often as high as one-tenth of a second, which is a substantial interval when considered in view of the high rate of speed that modern bombers attain. As noted above, a large power input to the magnet is necessary, because the magnet must exert a large force through an appreciable distance in a

short time. By way of illustration, the magnet may be required to exert a force of as much as twenty-five pounds through a distance of one inch in a time of approximately 0.04 second. This corresponds to about 0.1 mechanical horsepower actually developed and would require with the usual magnetic device an average electrical input of twenty amperes at twelve volts during the motion. As can be seen, this comprises a substantial power requirement.

Other bomb holding and releasing mechanisms are purely mechanical, and depend upon a system of cables, pulleys and levers to effect bomb release. Apparatus of this character, of course, detracts from the useful load of the plane, and in operation occasions even greater inaccuracy on the part of the operator. It is accordingly another object of this invention to obviate the above difficulties in a thoroughly practical and efficient manner.

Referring first to Figure 1, a pair of magnets generally indicated at 5 are supported in any suitable manner by a suitable portion of the under structure 11 of an aeroplane (not shown). Magnets 5 are provided with armatures 12 which are directly attached to a bomb 13. Magnets 5 are preferably connected in series, but if desired may be connected in parallel with a source of current 14, a manually operable switch 15 being provided to energize and deenergize magnets 5. When switch 15 is closed, the magnets are energized so as to attract thereto their armatures 12, and accordingly suspend the bomb until such time as switch 15 is opened to deenergize the magnets. When switch 15 is opened, bomb 13 is instantaneously released, by reason of the character of magnets 5 described below.

In Figure 3, I have shown a section through a magnet 10 generally similar to but differing in certain respects from magnet 5, this magnet being of a type suitable for effecting the instantaneous release desirable in bomb holding and releasing mechanism. Magnet 10 includes an iron body 16, in which a non-magnetic rod 17 is reciprocably disposed. An annular recess 18 formed in magnet body 16 has disposed therein a coil 19 having a suitable number of turns and layers of wire to energize the magnet. The upper portion of magnet body 16 is reduced as at 20, and the outer periphery of this portion is threaded for attachment thereto of a cap 21 or the like. Rod 17 extends through magnet body 16, and has a circular plate 22 secured to the top thereof, this plate being reciprocable in a circular recess formed by annular recess 20a. A coil spring 23 is disposed within cap 21 and presses downwardly against plate 22 so as constantly to bias the rod downwardly, as viewed in Figure 4. The lower end of rod 17 is reduced and threaded for attachment to an armature 25.

As is better shown in Figure 4, magnet body 16 is provided with a plurality of equally spaced radial slots 24 which extend in the plane of the axis of rod 17. Preferably armature 25 (Figure 3) is provided with similar slots. The provision of these slots 24 (Figure 4) has the effect of laminating the solid iron structure of the magnet so as to prevent the formation of eddy currents in the iron portions thereof when the magnetic field is suddenly collapsed for the purpose of release. In order that the magnet release time be short, it is necessary that the magnetic holding force, and hence the magnetic field be removed in the shortest possible time. This is accomplished by opening the current supply to the coil,

and hence removing the ampere-turn excitation of the magnet. Eddy currents act in the same manner as the normal ampere-turn excitation, and hence would frustrate attempts to produce a quick release. Through the provision of slots 24, the path of the eddy currents is effectively broken up, and the effect of such currents is, of course, greatly mitigated.

Referring back to Figure 3, rod 17, which supports armature 25, is preferably non-magnetic and slides in a bronze bushing 26. Downward travel of rod 17 and armature 25 is, of course, limited by plate 22 which in its lowermost position engages a stop formed in the upper portion of magnet body 16. When magnet 10 is energized, armature 25 is, of course, attracted to the pole faces 28 of the magnet and the minimum separation between armature 25 and pole faces 28 of the magnet body is determined by the thickness of a non-magnetic washer 29 secured adjacent the pole faces in annular recess 18. It is desirable that this gap be made as small as possible so that the stored energy of the field be reduced to a minimum.

Through the provision of spring 23, armature 25 is forced away from pole faces 28 upon deenergization of the magnet with a substantially strong force, which may be on the order of one-eighth of the magnet holding force. The full effectiveness of spring 23 is required only when armature 25 is very close to or in contact with the pole faces. In connection with the operation of spring 23, it should be noted that the bomb as carried in any one holding device may well vary in weight in a ratio of ten to one. Hence, the force at which the magnet will release will vary in the same ratio. An extremely low release force is undesirable because the actual time of release becomes less certain due to the effect of eddy currents and magnetic hysteresis in the iron. The spring therefore does not increase the release force of a heavy bomb greatly on a percentage basis, but does increase it greatly for a light bomb. It should also be noted that the combined effect of spring 23 and the non-magnetic gap minimize residual magnetic effects due to hysteresis in the various iron parts.

Under certain circumstances a magnet of a type somewhat different from that shown in Figure 3 may be used. To this end I provide a magnet generally indicated at 100 (Figure 8) comprising a stack of laminations 101 (Figure 9) each generally E-shaped and including a base portion 102 and arms 103, 104 and 105 (Figure 8). To maintain the stack of laminations 101 flat, heavier end plates 106 and 107 (Figure 9) are provided at opposite ends of the stack, the end plates and laminations being held together by rivets 108 (Figure 8) so placed as to prevent eddy currents.

In the spaces 109 and 110 formed between arms 103, 104, and arms 104, 105, is disposed a suitable bobbin 111 on which a coil 112 is wound (see also Figure 9).

An armature, generally indicated at 113, is also laminated and is accordingly formed of a number of strips 114 (Figure 9) riveted together by rivets 115 between heavier end plates 116. A clevis 117 is attached in any suitable manner to armature 113.

Although not shown herein, a spring, such as spring 23 (Figure 3) may be used if desired, in conjunction with magnet 100 (Figure 8) for the same purpose as described above.

Referring back to Figure 1, it may accordingly be seen that bomb 13 is supported directly by the

magnetic force of magnets 10 without the intervention of a mechanical system to carry the weight of the bomb. Magnets 5 are normally energized, and hence are only deenergized when it is desired to drop the bomb. By the use of magnets such as hereinabove described, release of the bomb is substantially instantaneous upon breaking of the energizing circuit of the magnets.

With reference to Figure 2, wherein there is shown a modified form of my bomb holding and releasing device, a bomb 30 having a hook 31 is supported by the free end 59a of a lever 59 having a fixed pivot 60 disposed in the bomb bay (not shown) of the airplane. The lever is held in such a position that its tip 59a is spaced a short distance from a fixed stop 61, this position of the lever being maintained by an arming pin 62 which is vertically slidable in a suitable guide 6, or the like. When arming pin 62 is in its lowermost position, lever 59 is maintained in bomb holding position as the arming pin prevents counterclockwise movement of the lever. The upper end of lever 59 is connected to armature magnet 25 by a link 63 so that upon energization of magnet 10 armature 25 is attracted thereto, causing slight clockwise movement of lever 59 which is possible by reason of the clearance between lever tip 59a and stop 61. When the magnet has been energized, arming pin 62 may be freely withdrawn from its bomb holding position as the upper end of lever 59 moves slightly clockwise by reason of the space provided between lever tip 59a and support 61. Subsequent deenergization of the magnet thus effects instantaneous release of bomb 30.

Referring now to Figure 10, wherein there is shown still another form of my apparatus, a magnet generally indicated at 118 is suitably secured to a pair of oppositely extending flanges 119 and 120 (Figure 11) preferably formed integrally with a pair of side plates 121 and 122, respectively, of a bomb shackle generally indicated at 123 in Figure 10. Referring back to Figure 11, magnet 118 includes a housing 124 which is preferably cylindrical in form and on the top of which is mounted a cap 125. Cap 125 carries a terminal head 126, adapted to receive electric conduits (not shown).

Within housing 124 is disposed a cylindrical shell 127 or the like, this shell and also housing 124 resting on and being secured to a bottom plate 128 which is in turn connected to flanges 119 and 120, the bottom plate having a hole 129 formed therein for purposes described below. Within the upper portion of shell 127 is mounted an iron core 130, this core being fixed to shell 127 and accordingly immovable relative thereto. Core 130 is reduced as at 131 and its bottom surface 132 provides suitable pole faces for the magnet. An armature 133 is movably disposed within shell 127 below core 130 and also includes a reduced portion 134, the diameter of which is the same as that of reduced portion 131 of core 130. Thus the two reduced portions of the core and armature provide an annular space within which a coil 25 is disposed, this coil being fixed relative to core 130. A sleeve 135 is connected in any suitable manner to an enlarged portion 136 of armature 133 so that upon energization of the magnet sleeve 135 and armature 133 move together.

Core 130 is provided with a recess 137, a similar recess 138 being formed in the upper part of armature 133, and in these two recesses is disposed a spring 139. The purpose and func-

tion of spring 139 is similar to that of spring 23 (Figure 3) of magnet 10, i. e. upon deenergization of magnet 118 (Figure 11) the forces acting on armature 133 which tend to draw it downwardly from core 130 are augmented by the thrust of spring 139 so as rapidly to separate the upper surface of armature 133 from pole faces 132.

A stud or the like generally indicated at 140 is threaded into the lower end 136 of armature 133 and includes a reduced portion 141 formed between a collar 142 and a lower bifurcated end 143. An armature 144 is rotatably mounted as by a bushing 145 on reduced portion 141 of stud 140, and carries at its opposite ends a pair of bobbins 146 and 147 on which are respectively mounted coils 148 and 149 (see also Figure 12).

Still referring to Figure 12, shell 127 has formed thereon 180° apart a pair of pole pieces 150 and 151, each being provided with a stop 152 and 153, respectively. Upon energization of coils 148 and 149, armature 144 rotates, i. e. its ends are attracted to pole pieces 150 and 151 until these ends abut stops 152 and 153.

As may be seen in Figure 11, a hub portion of armature 144 is attached as by a spacer collar or the like 154 to an arm 155 which is accordingly rotatable with armature 144 about the reduced portion of stud 140. As shown in Figure 12, arm 155 may be substantially equal in length to the diameter of housing 124, and accordingly extends through slots 156 and 157 formed in the sides thereof, shell 127 being similarly slotted. The upper portion of each of these slots is elongated as shown at 158 (Figure 11) each of the slots thus being generally of the shape of an inverted L (see also Figure 10). It may now be seen that when armature 144 (Figure 12) is rotated by reason of the energization of coils 148 and 149, arm 155 rotates therewith in counterclockwise direction to the dotted line position into the upper portions 158 of the slots. When in this position armature 133 (Figure 11) is not locked against downward movement and depends on the magnetic force thereon to prevent release. Upon deenergization of coils 148 and 149, however, arm 155 (Figure 12) may swing back into slots 156 and 157 under the bias of spring 159, this spring having one end connected to arm 155 and the other suitably connected to the bottom of pole face 150. It should be noted that movement of arm 155 by coils 148 and 149 is impossible unless magnet 118 is energized to lift plunger 133 and thus remove the load from arm 155.

As shown in Figure 11, clevis 143 is connected to the upper end of a link 160, which extends downwardly through hole 129 in bottom plate 128 into the space between a pair of plates 161 and 162 secured to side plates 122 and 121, respectively, of shackle 123. The lower end of link 160 (Figure 10) is pivotally connected to a lever 163 having a fixed pivot at 164 on shackle 123. Lever 163 includes a top surface 165 which supports a plate 166 having a fixed pivot at 167 on the bomb shackle. A lever 168 is pivoted to plate 166 as at 169 and has a fixed pivot at 170 on a suitable lug or the like 171 extending from an elongated arm 172 reciprocably mounted between plates 161 and 162 (Figure 11) in the upper portion of shackle 123. Arm 172 is generally U-shaped in cross section and is provided with a slot 173 through which a strut 180 extends.

To the opposite ends of arm 172 are pivoted a pair of links 179 and 180 which respectively have

fixed pivots at 181 and 182 at the ends of shackle 123. Levers 179 and 180 are respectively provided with holding ends 183 and 184 which are movable between open and closed positions with respect to slots 185 and 186 formed in the ends of shackle 123. These slots are provided to receive the supporting hooks (not shown) of the bomb, so that the bomb may be suspended from the shackle.

It will now be seen that when a bomb is supported in shackle 123, the weight of the bomb is transmitted through levers 179 and 180 in such a manner as to force arm 172 to the right. This force, in turn, presses plate 166 against lever 163 which in turn pulls link 160 downwardly. This force tends to draw link 160 (Figure 11) downwardly and does not effect such downward movement when magnet 118 is deenergized and arm 155 is in registry with slots 156 and 157.

When coils 148 and 149 (Figure 12) are deenergized, arm 155 is in the full line position wherein it supports the weight of the bomb as transmitted through link 160 (Figure 11). When, however, magnet 118 is energized, its armature 133 is attracted upwardly against core 130 and at the same time arm 155 (Figure 12) swings counterclockwise by reason of the energization of coils 148 and 149, which is simultaneous with the energization of the magnet. It should also be noted that the arm is free to swing by reason of the transmitted weight of the bomb being removed therefrom and supported entirely by the magnet. By reason of the arm's swinging and registry with slots 156 and 157, the ends of the arm are free to ride down these slots upon deenergization of the magnet. Further in this connection bobbins 146 and 147, on which the coils 148 and 149 are mounted are preferably made of copper or similar material and accordingly act as lag coils upon deenergization of coils 148 and 149, the deenergization of these latter coils being simultaneous with the deenergization of the magnet. Hence the bobbins cause the magnetic flux produced by coils 148 and 149 to decrease at a rate slower than that of the flux produced by coil 251 (Figure 11) in magnet 118. Hence, when magnet 118 is deenergized, link 160 is free to move immediately downward, by reason of the transmitted weight of the bomb exerted thereon, and during this downward movement arm 155 rides downwardly in slots 156 and 157. Of course, as link 160 moves downwardly the system of levers, including levers 163, 168, arm 172 and levers 179 and 180 are rapidly moved into their release position by reason of the force of gravity acting on the bomb. This bomb releasing movement is also expedited by the provision of spring 139 (Figure 11) which tends to increase the rapidity with which armature 133 separates from core 130.

When it is desired to restore the apparatus to bomb holding position, link 160 is raised in any suitable manner until bar 155 reaches the level of upper portions 158 of slots 156 and 157, the various coils, of course, being deenergized. When the arm reaches this position spring 159 (Figure 12) moves the arm clockwise into slots 158, and the apparatus is thus restored to what might be termed mechanical bomb holding position.

It may now be seen that with the apparatus of Figure 10 the bomb may be securely held without the necessity of energizing magnet 118 until just before it is desired to release the bomb. When it is desired to release the bomb, magnet 118 becomes the principal bomb holding factor

by reason of its energization, the safety device provided by arm 155 (Figure 12) being moved out of bomb retaining position so that deenergization of the magnet and of the coils 148 and 149 results in immediate bomb release, as described above. It will be understood that this last-described form of my apparatus, i. e. as shown in Figures 10, 11 and 12, may be controlled by nature of the circuits shown in Figures 5, 6 and 7. It will of course be understood that magnet 118 (Figure 11) may be of the same general type as that shown in Figures 3 and 4, or may be of the laminated type shown in Figures 8 and 9, depending upon which is the more desirable under the given circumstances.

It may now be seen that in any of the several forms of my apparatus hereinabove described, substantially instantaneous release of the bomb may be effected, when desired. As hereinbefore noted, it is desirable that a rapid collapse of the magnet field be effected in order to attain quick bomb release. To accomplish this rapid collapse, it is not only necessary to prevent eddy currents, but also the stored magnetic energy of the field must be quickly dissipated or removed. Mere interruption of the magnet circuit by means of the switch usually results in an arc which allows the magnet current to be sustained for a relatively long time because of the low resistance of the arc. To mitigate the formation of a detrimental arc, I have provided the circuit shown in Figure 5. The inductance and resistance of magnet 10 are indicated at 64 and 65, respectively, and the terminals 66 and 67 of the magnet are shunted by a condenser 68. Terminal 66 is connected to condenser 68 by lines 69 and 70, magnet terminal 67 being connected thereto by lines 71 and 72. Line 69, which includes therein a switch 73 preferably of the quick break type is connected to a battery 74. Line 71, which includes a switch 75 is also connected to battery 74. Switch 73 is normally closed while switch 75 is normally open, the latter being closed only when it is desired to energize the magnet.

Assuming that switch 75 is closed and the magnet energized by battery 74, the current through the magnet will be in the direction shown by the arrow A (Figure 5) with the battery polarity as shown. Condenser 68 is accordingly charged to the same voltage as the battery and will have the polarity indicated. When magnet deenergization is desired, quick break switch 73 is opened. At the instant this switch is opened, condenser 68 will maintain the potential across the magnet and the magnet current will be diverted through the condenser in the direction of arrow B. This will cause the condenser to discharge as it supplies energy to maintain the magnet current. As the surge of current continues, the condenser polarity reverses, resulting in the condenser being charged by the stored energy of the magnet. This process continues until the magnet current falls to zero, at which time the stored energy of the magnet is, of course, zero. The current will next reverse and the energy stored in condenser 68 will be returned to the magnet. In this manner, an electrical oscillation will be produced, the period of the oscillation being determined by the relative values of the effective magnet inductance and the capacitance of the condenser. The damping of the oscillation will depend on the losses of the circuit. The damping factor can be increased, if desired, and hence the oscillation more quickly

attenuated as, for example, by shunting magnet 10 and condenser 68 by a resistance 82 connected to lines 69 and 71.

When the magnet release circuit is timed by condenser 68 (Figure 5) the magnetic flux falls with great rapidity to zero and then builds up in the opposite direction because of the oscillation produced. This happens so fast that armature 25 (Figure 3) moved by the force of gravity alone would not have time to get out of the field of force of the magnet during the interval that the flux has fallen to the release value, passed through zero, and built up in the opposite direction to a value sufficient to hold the armature. To prevent this, I have provided a clearance indicated at 83 (Figure 3) between the armature clevis 25a and a rod pin 45 which attaches link or strut 63 to armature 25 (see also Figure 3). Thus, when the flux falls to the release value, rapid initial movement of the armature by spring 23 (Figure 20) is effected, and by reason of clearance 83 armature 25 quickly moves out of the field of force of the magnet and hence prevents pickup thereby on the second rise of the flux.

It is sometimes advantageous to increase the damping of the oscillation by inserting a resistance in series with condenser 68 (see Figure 6). This increases the resistance of the circuit for the oscillating current, but does not affect the operation of the magnet from the battery. Likewise, the condenser 68, or a part of it, may be placed in shunt with switch 73. A circuit combining all of these elements is shown in Figure 6, wherein a resistance 76 is shown in series with condenser 68, and at least a portion of condenser 68 is placed in shunt with switch 73.

With reference to Figure 7, I have shown a circuit for supplying magnet current from the plate circuit of a high vacuum tube generally indicated at 77. Magnet 10 has its coil 19 connected in the plate circuit of tube 77, and the plate power is supplied from a battery 78. The tube grid 77a is connected to a quick acting switch 79, and when coil 19 is to be energized, switch 79 is closed against contact 80. This results in a zero bias on grid 77a and allows a large plate current to flow. When deenergization of coil 19 is desired, switch 79 is moved to a contact 81, which is connected to a battery 84. Engagement of the switch with contact 81 places a high negative bias on the grid which causes the plate resistance of tube 77 to increase to a relatively large value, and hence causes the current through coil 19 to die away with great rapidity. It will thus be seen that where the circuit of Figure 7 is used, all possibility of any arcing or sparking in the magnet circuit is precluded. Hence there is eliminated any possibility of variation in release time due to this cause.

Certain bombing missions require a type of bombing sometimes termed "train bombing" wherein the bomber carries a large number of relatively small bombs which are sequentially released at the desired time. Bombing of this type accordingly requires bomb shackles equal in number to the bombs carried, and the bombs should be released in correctly timed sequence in order to effect the correct pattern necessary for accuracy.

To this end a desired number of shackles, such as shown in Figure 10, for example, are secured to the airplane, and are controlled by the circuit shown in Figure 13. In this circuit the bomb supporting magnet coils are indicated at B¹, B² and B³, while the coils 148 and 149 (Figure 12) which

control arm or latch 153 are indicated at L¹, L² and L³. One side of coils B¹, B² and B³ is each respectively connected by lines 190, 191 and 192 to a line 193 which is in turn connected to one side of a battery 194. The other side of battery 194 is connected by a line 195 to a terminal 196 of a switch generally indicated at 197. Switch 197 includes two or more additional terminals 198, 199 and 200, respectively connected to lines 201, 202 and 203, in turn connected respectively to the other sides of coils B¹, B² and B³. Thus these coils may all be connected across battery 194 at one time by a switch arm 204, when the arm is in the position shown in Figure 13. Preferably condensers C¹, C² and C³ are connected in the circuits of coils B¹, B² and B³, respectively, in shunt with switch 197 similarly as shown in Figure 6.

One side of latch coils L¹, L² and L³ (Figure 13) are connected by lines 205, 206 and 207 to one side of battery 194 by way of line 193, the other side of these coils being connected by lines 208, 209 and 210 to a line 211 connected to the other side of battery 194 by way of line 195. Lines 208, 209 and 210, respectively, include switches 212, 213 and 214 for control of the individual latches. Thus, if it is desired to release the bombs supported by magnets B¹ and B², switch 204 is closed, as shown, as are also switches 212 and 213. Thus, when switch arm 204 is opened, the bombs held by magnets B¹ and B² are released, in timed sequence but the bomb held by magnet B³ is not released as its safety latch L³ was not energized to bomb releasing position, as its controlling switch 214 was left open. Of course, if all the safety latch switches 212, 213 and 214 are closed, then all of the bombs are released upon opening of the magnet circuit by movement of arm 204.

As shown in Figure 13, latch coils L¹, L² and L³ can be connected separately. If desired, however, they can be wired in parallel with the main magnet coils B¹, B² and B³. The first type of connection provides somewhat greater flexibility of operation in that mechanical bomb suspension may be returned to after magnet energization. In the second type of connection both the latch and magnet coil are excited simultaneously, making it impossible to return to mechanical suspension subsequent to main holding magnet energization, as will be described below.

As shown in Figure 14 the latch coils L¹, L², L³ and L⁴ are wired in parallel to magnet coils B¹, B², B³ and B⁴ and as a switch arm 220 engages one or more of contacts 221-224 the corresponding latch and magnet coils are energized simultaneously. Switches 225-228 are preferably provided in the respective circuits so that any one or any combination thereof can be disconnected to preclude energization thereof and subsequent bomb release. The circuit in Figure 14 is used under circumstances as where it is not permissible to lift all bombs simultaneously as would be the case where the circuit of Figure 13 is used. As shown in Figure 14, bomb magnets B¹ and B³ might be in one bomb bay, while magnets B² and B⁴ might be in a different bay. Thus at any instant two magnets in different bays would be energized. If desired only one bomb magnet may be energized at a time, the only requisite being that the time required for energization be less than the desired time between bombs.

Thus, where train bombing is desirable, the several bomb shackle magnets may be energized and rapidly deenergized sequentially to effect rapid, timed release of the bombs at suitable

intervals. Furthermore any desired number of the total number of bombs may be released while retaining the rest against release.

Referring back to Figure 11, the structure shown therein is readily susceptible to what I term "reluctance-drop excitation" wherein the leakage flux of magnet 118 may be utilized to effect the desired movement of armature 144 and accordingly arm 155. Accordingly coils 148 and 149 may be dispensed with, if desired, and portion 136 of armature 133 may be thinned to the proper extent so as to produce a substantial increase in its magnetic reluctance. The flux lines, upon energization of magnet 118 will accordingly be concentrated in the area of pole faces 151 and 152 (see Figure 12) so that armature 144 will tend to orient itself with respect to the pole faces when the transmitted load of the bomb is removed from arm 155. Orientation or alignment of armature 144, of course, moves arm 155 into alignment with slots 156 and 157 through which the arm may pass upon magnet deenergization to release the bomb. It should be noted that the transmitted weight of the bomb plus the bias of spring 139 moves magnet armature 133 so rapidly as to preclude re-entrance by spring 159 of arm 155 into horizontal slots 158 before the arm has passed below the entrance of these slots. The "reluctance-drop excitation" structure may be utilized in the circuits shown in Figures 13 and 14, the latch coils and their connections being omitted, of course.

In Figure 15 I have shown a pair of curves illustrative of an oscillogram which shows the release characteristics of the shackle of Figures 10, 11 and 12 for a load of about the maximum rated load of the shackle, and connected in a circuit such as is shown, for example, in Figure 6. The lower curve 230 is representative of a timing wave, the time between adjacent peaks thereof being one-thousandth of a second. The upper curve 231 is representative of the current of coil 251 (Figure 11). The horizontal line 232 represents the zero value of this current, while the horizontal line 233 shows the steady value of the magnet current while the coil is energized and prior to the release. At time X, the coil circuit is opened and the current decays from its steady value 233 to zero on the curve shown. At time Y the magnet plunger or armature starts moving, and at time Z the bomb hooks 183 and 184 commence to open. It will be noted that this time is slightly less than two-thousandths of a second after the initiation of the release at point X. The actual release, i. e. the release of the magnet armature 133, occurs in an even shorter time before the current first reaches zero. This operation results from the action of spring 139 and the weight of the bomb.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In bomb release apparatus or the like for supporting and rapidly releasing a mass, including a support, holding means associated with said mass to permit it to be supported by said support against forces tending to release it therefrom, magnetic material forming part of said holding means, and magnetic means for exert-

ing a magnetic force to attract said magnetic material to support said mass, the combination of circuit comprising magnetic means, a source of D. C. electric power for energizing said magnetic means to attract and hold a piece of magnetic material, a switch in said circuit operable to break said circuit to deenergize said magnetic means, and means in said circuit causing the decaying current existing therein after said circuit is broken to oscillate, whereby said piece of magnetic material is released more rapidly than would be the case if said oscillation did not exist.

5 2. In bomb release apparatus or the like for supporting and rapidly releasing a mass, including a support, holding means associated with said mass to permit it to be supported by said support against forces tending to release it therefrom, magnetic material forming part of said holding means, and magnetic means for exerting a magnetic force to attract said magnetic material to support said mass, the combination of a circuit comprising magnetic means, a source of D. C. electric power for energizing said magnetic means to attract and hold a piece of magnetic material, a switch in said circuit operable to break said circuit to deenergize said magnetic means, means in said circuit causing the decaying current existing therein after said circuit is 10 broken to oscillate, and resilient means urging said piece of magnetic material away from said magnetic means, whereby said piece of magnetic material is released more rapidly than would be the case if said oscillation did not exist.

15 3. In bomb release apparatus or the like for supporting and rapidly releasing a mass, including a support, holding means associated with said mass to permit it to be supported by said support against forces tending to release it therefrom, magnetic material forming part of said holding means, and magnetic means for exerting a magnetic force to attract said magnetic material to support said mass, the combination of a circuit comprising magnetic means including an iron body forming a magnetic circuit closed by an armature member, a source of D. C. electric power for energizing said magnetic means to hold said armature, said body and said armature each being provided with slotted portions to reduce eddy currents in said magnetic circuit 20 upon deenergization of said magnetic means, a switch in said circuit operable to break said circuit to deenergize said magnetic means, and means in said circuit causing the decaying current existing therein after said circuit is broken to oscillate, whereby said piece of magnetic material is released more rapidly than would be the case if said oscillation did not exist.

25 4. In bomb release apparatus or the like for supporting and rapidly releasing a mass, including a support, holding means associated with said mass to permit it to be supported by said support against forces tending to release it therefrom, magnetic material forming part of said holding means, and magnetic means for exerting a magnetic force to attract said magnetic material to support said mass, the combination of a circuit comprising a solenoid a source of D. C. electric power for energizing said solenoid to attract and hold a piece of magnetic material, a switch in said circuit operable to break said circuit to deenergize said solenoid and a condenser connected in parallel with said solenoid to form therewith a resonant circuit causing the decaying current existing therein after said circuit is 30 broken to oscillate, the inductance of said sole-

noid and the capacity of said condenser determining the frequency of oscillation of said decaying current, whereby said piece of magnetic material is released more rapidly than would be the case if said oscillation did not exist.

5. In bomb release apparatus or the like for supporting and rapidly releasing a mass, including a support, holding means associated with said mass to permit it to be supported by said support against forces tending to release it therefrom, magnetic material forming part of said holding means, and magnetic means for exerting a magnetic force to attract said magnetic material to support said mass, the combination of a circuit comprising a solenoid, a source of 10 D. C. electric power for energizing said solenoid to attract and hold a piece of magnetic material,

15 a switch in said circuit operable to break said circuit to deenergize said solenoid, a condenser connected in parallel with said solenoid to form therewith a resonant circuit causing the decaying current existing therein after said circuit is broken to oscillate, the inductance of said solenoid and the capacity of said condenser determining the frequency of oscillation of said decaying current, and a resistor connected in parallel with said solenoid and said condenser to damp the oscillation in the resonant circuit formed thereby to speed the decay of said transient current, whereby said piece of magnetic material is released more rapidly than would be the case if said oscillation did not exist.

HERBERT C. ROTERS.
